UNITED STATES PATENT OFFICE.

GEORGE D. POGUE, OF ST. LOUIS, MISSOURI.

LUBRICATING MECHANISM FOR PISTON-MACHINES.

1,230,513.

Specification of Letters Patent. Patented June 19, 1917.

Application filed February 23, 1917. Serial No. 150,481.

To all whom it may concern:

Be it known that I, GEORGE D. POGUE, a citizen of the United States, residing at St. Louis, Missouri, have invented a certain new and useful Improvement in Lubricating Mechanisms for Piston-Machines, of which the following is a full, clear, and exact description, such as will enable others skilled in the art to which it appertains to make and use the same.

This invention relates to a lubricating mechanism for piston machines of the type in which a part that moves with the piston cooperates with a stationary part to force oil through a conduit that leads to a piston pin bearing or other bearing or part that requires lubrication.

The main object of my present invention is to provide a lubricating mechanism of the general type referred to, which is so constructed that perfect longitudinal alinement of the two cooperating parts of the mechanism is not essential to insure successful operation of the mechanism. To this end I have devised a lubricating mechanism that comprises an oil pump carried by a stationary part of the machine and a device that moves with the piston of the machine and actuates the plunger of said pump for a small part of the stroke of the piston.

Another object is to provide a lubricating mechanism of the kind just described, in which the plunger of the pump remains at all times in the cylinder of the pump, the mechanism being so constructed that ample time is provided at each cycle of operations of the machine for the oil to flow from the source of supply into the cylinder of the pump, and thus be in readiness to be forced into the oil conduit at the next cycle of operations.

Another object is to provide a lubricating mechanism of the character described that is exceptionally strong and rugged and provided with an easily adjustable means for accurately regulating the discharge of oil from the pump.

Another object is to provide a lubricating mechanism of the general type referred to that is provided with a novel means for preventing back flow of oil through the oil conduit that leads from the pump to the bearing or part being lubricated.

Another object is to provide a lubricating mechanism for machines that comprises an oil conduit formed by two normally sepa-

rated tubular members that are connected together by a butt joint when they are brought into engagement with each other, and means for forcing oil through said conduit when the abutting ends of the two parts of same are in engagement with each other.

Another object is to provide a lubricating mechanism of the character just referred to that is equipped with a means for catching and returning to the lower section of the conduit any oil that escapes through the butt joint between the two parts or sections of the conduit.

Still another object is to provide a lubricating mechanism of the general type referred to which is so constructed that any air which becomes trapped with the oil flowing through the conduit leading from the pump can escape before it reaches the bearing or part being lubricated. Other objects and desirable features of my invention will be hereinafter pointed out.

Figure 1 of the drawings is a vertical sectional view of a portion of a piston machine equipped with a lubricating mechanism constructed in accordance with my present invention.

Fig. 2 is a vertical sectional view, taken on the line 2--2 of Fig. 1.

Fig. 3 is a horizontal sectional view, taken on the line 3--3 of Fig. 1.

Figs. 4, 5 and 6 are horizontal sectional views of the oil conduit, taken on either of the lines 4--4 of Fig. 2, illustrating various capillary devices that can be used in the oil conduit to prevent back flow; and

Fig. 7 is a detail view, illustrating an ordinary ball check valve that can be used in place of a capillary device to prevent back flow through the oil conduit.

Referring to the drawings, which illustrate the preferred form of my invention, A designates the cylinder of an engine or machine, B designates the piston that is reciprocatingly mounted in said cylinder, C designates the crank on the crank shaft of the machine, and D designates the connecting rod that connects said crank and piston together. In the machine herein shown the piston and connecting rod are connected together by a piston pin E mounted freely in a bearing F on the connecting rod and having its end portions keyed or connected in any other suitable manner to lugs 1 on the interior of the piston, and the connecting rod D is provided on its lower end with a

bearing G that surrounds the crank pin H on the crank C.

One feature of my present invention consists in a lubricating mechanism provided 5 with an oil conduit formed by two normally separated sections or tubular-shaped parts whose adjacent ends are so shaped that they form a butt joint when said sections are brought together, and means for 10 forcing oil through said conduit when the two parts of same are butted together. It is immaterial, so far as my broad idea is concerned, how the oil is forced through said conduit, and it is also immaterial how the 15 two sections of the conduit are mounted and actuated so as to separate them and bring them together. In practice, I prefer to use a gasket or resilient element that is interposed between the two abutting ends of the 20 sections of the oil conduit when said sections are brought together. In the form of my invention herein shown the oil conduit above referred to comprises a tubular-shaped device J that moves with the piston B and a 25 tubular-shaped member that forms the plunger of a stationary pump I which is carried by a bracket 2 or other stationary part of the machine, the lower end of said device J and the upper end of the pump plunger 30 being so formed that when they are brought together a butt joint will be formed between said parts. The pump I and device J are so arranged that said device J will engage the plunger of the pump I for a small part 35 of the stroke of said piston, thereby causing oil to be forced from the cylinder of the pump into a conduit that forms an extension of the device J and which leads either directly to the bearing or part being lubricated or to an oil reservoir 3, as shown in 40 Fig. 1, that is mounted on one of the lugs 1 of the piston, the oil that is supplied to the oil reservoir 3 being subsequently delivered to the piston pin bearing F through oil distributing ducts 3^b formed in the lug 1 that carries said oil reservoir and in the piston pin E, as shown in Fig. 1. If desired, a 45 similar mechanism can be provided for lubricating the crank pin bearing G, the oil reservoir 3^a of the crank pin bearing lubricating mechanism being mounted on the connecting rod D, as shown in Figs. 1 and 3 and so formed that the oil conduit K' will always remain in operative position with 50 relation to same when the machine is in operation.

The oil pump previously referred to comprises a cylinder 4, a tubular-shaped plunger 5 that is reciprocatingly mounted in said 55 cylinder 4 and provided at its lower end with a check valve 5^a, a spring 6 that moves the plunger 5 upwardly, and an adjustable element 7 that governs the stroke of the plunger 5. The spring 6 is preferably ar- 60 ranged in the cylinder 4 between the bottom

of said cylinder and the lower end of the plunger 5, and the oil supply pipe 8 through which the oil is supplied to said cylinder 4 is connected to the lower end of same and is provided with a check valve 9 or other suitable device that prevents back flow through said oil supply pipe 8 during the displacement stroke of the pump plunger. If desired, the pipe 8 can be provided with a valve 8^a for regulating the flow of oil 70 through same. 75

The tubular-shaped device J that depresses the plunger of the pump is preferably mounted on the piston B in such a manner that the opening or passageway running 80 through the center of said device will be in substantially vertical alignment with the center bore of the pump plunger 5. In the form of my invention herein shown the device J is carried by an air chamber L arranged on the inside of the piston B adjacent the lower end of same, which air chamber is connected by means of the oil conduit K with the oil reservoir 3, previously described. It is not essential, however, that 85 the device J be mounted in this exact manner, but it is essential that it be provided with a center bore or passageway that communicates with the oil conduit K, so that the oil which is forced upwardly into said device J by the downward movement of the plunger of the pump I will enter the oil conduit. I prefer, however, to equip the mechanism with an air chamber L, as such an air chamber causes the intermittent or 90 pulsating flow of the oil through the device J to be converted into a substantially continuous flow through the conduit K by the pressure in the chamber L. If desired, the plunger 5 of the pump can be provided with 95 an automatically operating relief valve 10 that governs a lateral discharge port 10^a leading from the center bore of the pump plunger, so as to relieve the pressure in the passageway through which the oil flows 100 from the cylinder of the pump, in case of a temporary stoppage or diminution in the flow of the oil through said passageway, due, for instance, to low temperature. The 105 oil that enters the tubular-shaped device J on the piston B and the oil conduit K that communicates with said device, is prevented from flowing backwardly through the oil passageway formed by said elements, either 110 by means of a capillary device 11 arranged 115 in the device J, as shown in Fig. 1, or a ball check valve or other suitable type of check valve 11^a arranged in the device J, as shown in Fig. 7. The oil that enters the hollow plunger 5 of the pump is prevented from 120 flowing back into the cylinder 4 by the check valve 5^a at the lower end of the pump plunger. I prefer to use a capillary device 11 to prevent back flow of the oil through the 125 oil passageway leading from the pump to 130

the bearing or part being lubricated, on account of the fact that a capillary device is less liable to get out of order than a check valve that opens and closes, and it will sustain a column of oil, even though the oil column be of great height, without seriously restricting or impeding the flow of oil from the pump plunger into the device J. Another advantage that results from using a capillary device to prevent back flow of the oil through the oil conduit is, that a capillary device can be arranged throughout the entire length of the oil passageway, thereby causing the oil column to be sustained throughout its entire height, instead of at one point by a single member at the lower end of the passageway, such, for example, as a check valve. It is immaterial what type of capillary device is used for this purpose, so long as said device is constructed in such a manner that sufficient small openings or spaces are provided in same to permit the oil to pass in one direction through said device but not return or flow in the opposite direction through said device. Figs. 4, 5 and 6 of the drawings illustrate various forms of capillary devices 11 that may be used for the purpose mentioned, the one shown in Fig. 4 comprising a tubular center portion from which a plurality of ribs or veins radiate, the one shown in Fig. 5 being formed from a sheet of suitable metal that is coiled into a roll, and the one shown in Fig. 6 consisting of a bundle of wires arranged in the oil passageway. Still another form of capillary device that may be used is one formed by a number of relatively small tubes arranged in multiple.

The plunger 5 of the pump I is provided at its upper end with a head piece 5^b whose diameter is considerably greater than the portion of the plunger that fits in the cylinder of the pump, so that slight inaccuracies in the longitudinal alinement of the pump plunger and the actuating device J on the piston will not interfere with the successful operation of the mechanism. The head 5^b of the pump plunger is preferably provided with a removable wear piece 12, preferably made of resilient material, against which the lower end of the device J strikes, which wear piece is clamped in operative position by means of a clamping device 13 on the head of the plunger that also serves as a collector for any oil that escapes from the joint between the lower end of the device 5 and the gasket 12, the oil that collects in the device 13 flowing back into the hollow plunger 5 of the pump. The adjustable element 7, previously referred to, that governs the stroke of the plunger, preferably consists of a sleeve-like or tubular-shaped member screwed onto an externally screw-threaded portion 14 on the cylinder 4 of the pump and provided at its upper end with a

flange or rim 7^a that serves as a stop or abutment which coöperates with the head on the pump plunger, or rather the clamping device 13 on said head to limit the upward stroke of the pump plunger. By turning the element 7 in one direction or the other the height of the flange or rim 7^a thereon can be varied, thereby enabling the supply of oil from the pump to be accurately controlled. Any suitable means can be used for retaining the element 7 in adjusted position, the means herein shown for this purpose consisting of a plurality of spring-pressed pins 15 in said element that coöperate with notches 16 formed in the top side of a flange 17 on the pump body.

When the machine is in operation the device J on the piston B of the machine engages the head on the plunger of the pump I at each cycle of operations of the machine and forces said plunger downwardly into the cylinder of the pump, thereby causing the oil in said pump cylinder to be forced upwardly through the center bore in the plunger and in the device J, into the oil conduit K. The pump I is so arranged with relation to the actuating device J on the piston of the machine that the plunger of the pump is actuated for only a small part of the stroke of the piston, thereby providing ample time for the oil from the source of supply to enter the cylinder of the pump at each cycle of operations of the machine. The plunger of the pump remains at all times in the cylinder of the pump, and as the actuating device J on the piston merely strikes against the end of the pump plunger, instead of entering an opening or socket in said plunger, a slight inaccuracy in the longitudinal alinement of said parts will have no effect on the successful operation of the mechanism, or cause any parts of same to be broken or bent out of shape. The quantity of oil that is supplied to the oil conduit K at each cycle of operations of the machine can be accurately controlled by the valve 8^a in the supply line 8 or by simply adjusting the element 7 upwardly or downwardly, so as to vary the stroke of the plunger of the oil pump. I prefer to equip the mechanism with an oil reservoir 3 into which the oil is fed by the pump I and from which the oil flows to the bearing or part being lubricated, as such a reservoir permits any air that has become trapped with the oil that flows through the conduit K to escape from said conduit before the oil reaches the bearing being lubricated. This oil reservoir 3 is not essential, however, to the successful operation of my improved lubricating mechanism.

Having thus described my invention, what I claim, and desire to secure by Letters Patent, is:

1. In a machine of the character de-

- scribed, a reciprocating piston, an oil pump mounted on a stationary part of the machine and comprising a cylinder and a tubular plunger reciprocatingly mounted in said cylinder, a device carried by the piston of the machine that engages said pump plunger and forces the oil in the cylinder of the pump through the bore in said plunger, and an oil conduit that communicates with the bore in said plunger and through which the oil is conducted to the part being lubricated.
2. In a machine of the character described, a reciprocating piston, an oil pump arranged stationary with respect to the movement of said piston and provided with a tubular plunger, a substantially tubular-shaped device carried by said piston and arranged in such a manner that it will engage and actuate said pump plunger and cause oil to be forced through said plunger and through said actuating device, and an oil passageway that communicates with said actuating device.
3. In a machine of the character described, a reciprocating piston, an oil pump carried by a stationary part of the machine, a device carried by the piston that is adapted to engage and actuate the plunger of said pump, an oil passageway through which oil is forced by said pump, and an air chamber that communicates with the interior of said oil passageway.
4. In a machine of the character described, a reciprocating piston, an oil pump carried by a stationary part of the machine and provided with a plunger that has a passageway in same through which the oil in the cylinder of the pump is forced during the displacement stroke of the pump plunger, means carried by the piston of the machine for actuating said pump plunger, and an oil conduit or duct carried by the piston and arranged so that the oil displaced by the plunger of the pump will flow through same.
5. In a machine of the character described, a reciprocating piston, a stationary oil pump provided with a substantially tubular-shaped plunger through which oil is forced on the displacement stroke of the pump plunger, and an oil passageway carried by the piston and comprising a substantially tubular-shaped member that engages the plunger of the pump and actuates same when said piston moves in one direction.
6. In a machine of the character described, a reciprocating piston, an oil pump carried by a stationary part of the machine and provided with a plunger that has a passageway in same into which oil is forced from the cylinder of the pump on the displacement stroke of the plunger, a tubular-shaped actuating device on the piston that is adapted to engage and move said pump plunger, an air chamber that communicates with the interior of said tubular-shaped device, and an oil conduit leading from said air chamber.
7. In a machine of the character described, a reciprocating piston, an oil pump carried by a stationary part of the machine and provided with a substantially tubular-shaped plunger, a substantially tubular-shaped device on the piston whose end engages said pump plunger and moves it during part of the stroke of said piston in one direction, an oil conduit on the piston that communicates with said actuating device, and an adjustable abutment for limiting the movement of said pump plunger on its return stroke.
8. In a machine of the character described, a reciprocating piston, an oil pump carried by a stationary part of the machine comprising a substantially tubular-shaped plunger which is provided at one end with a head piece, and an oil passageway on the piston comprising a substantially tubular-shaped member whose end strikes against the head on said pump plunger and moves said plunger during part of the stroke of the piston in one direction.
9. In a machine of the character described, a reciprocating piston, an oil pump carried by a stationary part of the machine comprising a substantially tubular-shaped plunger which is provided at one end with a head piece, an oil passageway on the piston comprising a substantially tubular-shaped member whose end strikes against the head piece on said pump plunger and moves said plunger during part of the stroke of the piston in one direction, and an adjustable element that serves as a stop against which the head piece on said pump plunger strikes on the return stroke of said plunger.
10. In a machine of the character described, a reciprocating piston, a stationary oil pump provided with a substantially tubular-shaped plunger which has a head at one end of same, a removable wear piece on said head, and a device carried by the piston of the machine that strikes against said wear piece and moves said plunger when said piston moves in one direction.
11. In a machine of the character described, a reciprocating piston, an oil pump carried by a stationary part of the machine and provided with a reciprocating plunger that has an oil passageway therein into which oil is forced from the cylinder of the pump during the displacement stroke of the plunger, an adjustable member on said pump provided with a portion that serves as a stop or abutment which limits the movement of the pump plunger in one direction, a spring that actuates the pump plunger and normally holds it in engagement with said stop, and means carried by said piston for

moving said plunger during a portion of the stroke of the piston in one direction.

12. In a machine of the character described, a reciprocating piston, an oil pump carried by a stationary part of the machine and provided with a plunger that has a passageway in same through which oil is forced on the displacement stroke of the plunger, an oil passageway on the piston 5 comprising a substantially tubular-shaped member that engages said plunger and actuates it during part of the stroke of the piston in one direction, and means for preventing back flow through said oil passageway.
13. In a machine of the character described, a reciprocating piston, an oil conduit that travels with said piston, means for forcing oil through said conduit when the machine is in operation, and a capillary device 10 for preventing back flow through said conduit.

14. In a machine of the character described, a reciprocating piston, an oil pump mounted on a stationary part of the machine, a tubular-shaped device carried by the piston that actuates said pump during a portion of the stroke of the piston in one direction and causes oil to be forced upwardly through said device, and a capillary 25 means arranged in said device for preventing back flow of the oil through same.

15. A lubricating mechanism for machines provided with an oil conduit that comprises two normally separated parts or sections 30 constructed in such a manner that a butt joint will be formed between said parts when they are brought together, means for bringing said parts together and separating them, and means for forcing oil through 35 said conduit when the parts of same are together.

16. A lubricating mechanism for machines provided with an oil conduit that comprises two normally separated parts or sections 40 constructed in such a manner that a butt joint will be formed between said parts when they are brought together, means for 45

bringing said parts together and separating them, means for forcing oil through said conduit when the parts of same are together, 50 and a resilient element arranged so that it will lie between the abutting ends of the two sections of said conduit.

17. A lubricating mechanism for machines provided with an oil conduit that comprises 55 two normally separated parts or sections constructed in such a manner that a butt joint will be formed between said parts when they are brought together, means for bringing said parts together and separating 60 them, means for forcing oil through said conduit when the parts of same are together, and means for collecting and saving any oil that escapes through the butt joint between the two sections of the oil conduit. 65

18. In a lubricating mechanism of the character described, a moving tubular-shaped member that forms part of a conduit through which oil is forced, a co-operating tubular-shaped member arranged so that the 70 end of said moving member will butt against same and form a butt joint between said members, and means for forcing oil through said members when they are in engagement with each other. 75

19. In a lubricating mechanism of the character described, two tubular-shaped members that are normally separated, means for separating said members and bringing them together, a resilient element that lies 80 between the abutting ends of said members when they are brought together, and means for collecting any oil that escapes through the joint between said members.

20. In a lubricating mechanism of the 85 character described, two normally separated, tubular-shaped members that are adapted to be butted together so as to form part of an oil conduit, means for forcing oil through said members when they are together, and 90 means for preventing back flow through said members.

GEOERGE D. POGUE.
